United States Patent Office

Des. 179,491
Patented Jan. 1, 1957

179,491

PIN

Harry M. Osers, New York, N. Y.

Application May 28, 1956, Serial No. 41,687

Term of patent 3½ years

(Cl. D45—19)

Fig. 1

Fig. 2

Fig. 3

Fig. 1 is a front elevation view of a pin, showing my new design.

Fig. 2 is a side view thereof; and

Fig. 3 is a sectional view thereof taken on line 3—3 of Fig. 1.

The dominant features of my design reside in those portions shown in full line.

I claim:

The ornamental design for a pin, as shown and described.
